UNITED STATES PATENT OFFICE.

RICHARD CRAMP, OF LONDON, ENGLAND.

TURBINE.

No. 884,719.

Specification of Letters Patent. Patented April 14, 1908.

Application filed January 22, 1908. Serial No. 412,099.

To all whom it may concern:

Be it known that I, RICHARD CRAMP, a subject of the King of Great Britain, residing at London, England, have invented certain new and useful Improvements in Turbines, and of which the following is a specification.

This invention relates to turbines in which the blades of the rotary members are pivoted thereto, so that their angle can be altered automatically for the purpose of reversing the direction of motion, by admitting steam to alternative sets of guide vanes, set in opposite directions, the direction the pivoted blades set themselves and the direction of rotation depending upon which sets of guide vanes are selected for admitting and giving direction to the steam.

The present invention has for its object to construct the pivoted blades so that they are rocked over with certainty to the opposite position on the direction of inflow of steam to the said blades being reversed; to control the admission of steam to one or other series of oppositely disposed sets of guide vanes situated between each set of blades, and so that the quantity of steam may be reduced without reducing the speed of flow of the said steam admitted to the turbine as a whole, and the invention also includes features for simplifying the construction and arrangement of the turbine.

The invention will be described with reference to the example of construction shown in the accompanying drawings, in which:—

Figure 1 is a sectional side elevation of a part of a turbine constructed in accordance with the present invention. Fig. 2 is a sectional end elevation of same on the line 2—2 of Fig. 1. Fig. 3 is a diagram, on a larger scale, of some of the blades and vanes and of the reversing mechanism; the blades being shown in full lines in the position they occupy when driving in one direction and in dotted lines in the reverse position. Fig. 4 is a detail showing the mode of securing the blades.

In the drawings *a* is the casing, *b* the steam inlet, *c c* are the rotor blades which are mounted on disks *d d*. Each blade is pivoted on pins *e, e'* near the end remote from its guide vanes, while the other end is free to swing through a sufficient angle to permit the steam to act on one side thereof or on the other side so as to drive the turbine in either direction as desired. Stops *f, f'* are placed between the blades to limit their movement, and are of a curvature suitable for facilitating

the flow of the steam. The sides of each blade present a continuous curve to the steam, so that it can act thereon at the most efficient angle for the impulse action during its passage between the blades, and the free end of each blade is bifurcated or forked as shown at *g*.

Between the rings of rotor blades *c c* are stationary guide rings *h* carrying or formed with the guide vanes *i*, arranged alternately in groups of forwardly directed vanes and groups of backwardly directed vanes. Against the face of each of said guide rings are fitted slideable segments *k* constituting valves, and adapted to be so adjusted, relatively to the guide rings, as to cover either the forward or the reversing vanes, or both, or partly uncover either. A convenient means for holding and adjusting these segments consists in providing them with pins *k'* fitting freely in holes in rings *l*, provided on a part of their peripheries with worm teeth *m*, with which engage worms *n* mounted on shafts *o* by which they may be turned in either direction from a common shaft, to cause the segments to cover the sets of vanes for one direction, and to uncover the oppositely disposed sets.

A convenient mode of assembling the blades on each rotor disk *d* consists in mounting their pivot pins *e, e'* (which, in the example illustrated, consist of trunnions extending from the ends of and integral with the blades) in concentric annular rings *p, q*, of which *p* (Fig. 4) forms a shrouding while the other *q* may be a flange of the disk *d*, or a part attached thereto.

The lower trunnions *e'* of the blades rest in radial grooves or sockets *q'* formed partly in the radial face of the disk *d* or of the part carried by same, and partly in a ring or cover *r* which is secured over the same by bolts and nuts *r'*, or by other means.

The upper trunnions *e* project into or through slotted holes *p'* formed in the shrouding *p*, so that said trunnions can be passed laterally into their respective holes when the ring *r* is removed; they are then suitably retained therein, as by a loose ring or segments *s* interposed between the trunnions *e* and the radial face of the shrouding *p*, where the latter is L-shaped or flanged as in the present instance.

t are distributing or expansion spaces behind and between the sets of rotor blades, and *u v* are packing pieces and rings respec-

tively, which serve to prevent steam leaking from the expansion spaces t through the junction between the stationary frame and the hubs of the rotary disks d .

5 The groups of guide vanes i and the sliding segment valves are so arranged, that in the position shown at Fig. 2, all the groups of forwardly directed vanes are open to the steam pressure, while all the groups of rearwardly directed vanes are closed, and it will be observed that by operating the shafts o controlling a series of the angularly adjustable rings carrying the segments, through the medium of a common shaft, more or less in 10 number of each group of forwardly directed guide vanes i throughout the turbine can be submitted for the passage of the steam, and thus it will be understood that the quantity of steam admitted through the series of forwardly directed vanes can be reduced, without reducing the speed of flow of the said steam admitted through the turbine taken as a whole.

15 By actuating the shafts o in the opposite direction, through the medium of the common shaft aforesaid, all the segments may be angularly moved, so that the series of forwardly directed vanes becomes wholly closed, and a continuation of this angular movement 20 of the segments throughout the series of the turbine, will uncover the rearwardly directed vanes in all the stationary guide rings h more or less as required and so the area submitted for the passage of the steam through the directing vanes, is not only adjusted and varied for the first set of directing vanes, but simultaneously for each series of directing vanes in all the vane-carrying rings throughout this expansively working turbine, and a 25 perfect control is obtained by reason also of the fact that the slidable segment valves k can be made to move in proportion so that all the guide vanes of a series throughout the turbine are caused to present a proper proportion of complete ports for the passage of the steam, so that when half the ports of one 30 series of guide vanes in the first stationary ring are open, half the ports of the corresponding series in all the other rings of guide 35 vanes will be likewise opened, and when a quarter of the ports of a series in the first stationary ring are open, a quarter of the ports of the corresponding series in all the other stationary guide rings will be opened, and so on.

40 55 The steam being free to pass through a series or a portion of a series of directing vanes in each stationary guide ring, say in the direction of the arrows Fig. 3, the said steam jets will act on the faces of the rotor blades c and drive the turbine in one direction.

60 When, however, by means of the aforesaid common shaft, all the series of shafts o are operated until the steam is free to pass through the directing vanes, as for instance 65 is illustrated at the lower part of Fig. 3, it

will be obvious that the steam jets will act upon one arm of the bifurcation at the end of each pivoted rotor blade, and will cause each blade to be swung over into the dotted position shown at Fig. 3, and the turbine will be 70 driven in the reverse direction, while the number of directing vanes open for the passage of the steam can be accurately regulated throughout each stage of the expansion, and thereby the turbine can be employed with the greatest possible mechanical efficiency. After passing through the first series of rotor blades, the steam passes into the expansion space t , and from thence through the next series of directing vanes, 80 and so on, and finally to the exhaust.

85 What I claim as my invention and desire to secure by patent is:—

1. In a reversible turbine; the combination with a cylindrical casing, a revoluble shaft passing axially therethrough, end covers to the casing and bearings in the end covers to carry said shaft, blade-carrying rotor disks keyed at a distance apart on said revoluble shaft, a stationary guide ring located 90 within the casing in front of and adjacent to each rotor disk, said guide ring having an annular series of guide vanes arranged alternately in groups of forwardly directed vanes and groups of backwardly directed vanes, 95 and means for opening or closing one or other or both groups of said guide vanes, the casing having a steam inlet at one end to admit steam to the first stationary guide ring and an outlet at the other end of the casing; 100 of blades carried by the rotor disks, a pivot at the rear end of each rotor blade, bearings in the revoluble disks to carry said pivots radially to the revoluble shaft to permit said blades to freely swing about said pivots, 105 stop-pieces on said revoluble disks between said pivoted blades to limit the angular motion of said blades, and a bifurcation on the radial free edges of said rotor blades facing the steam inlet to provide surfaces for the 110 jets of steam to act upon to rock said blades into an opposite position upon change of direction of the incoming steam jets substantially as set forth.

115 2. In a reversible turbine; the combination with a cylindrical casing, a revoluble shaft passing axially therethrough, end covers to the casing and bearings in the end covers to carry said shaft, blade-carrying rotor disks keyed at a distance apart on said revoluble shaft, a stationary guide ring located 120 within the casing in front of and adjacent to each rotor disk, said guide ring having an annular series of guide vanes arranged alternately in groups of forwardly directed vanes and groups of backwardly directed vanes, 125 and means for opening or closing one or other or both groups of said guide vanes, the casing having a steam inlet at one end to admit steam to the first stationary guide ring 130

and a steam outlet at the other end; of stationary guide rings within the casing one located adjacent to and in front of each rotor disk, each guide ring having an annular series of guide vanes arranged in groups of forwardly directed and groups of backwardly directed vanes, said vanes being located opposite to said rotor blades, slideable segment valves located in contact with the face of said 5 guide rings to regulate the opening or closing of one or other or both groups of said guide vanes, a concentric bearing surface on the inlet side of each of said stationary guide rings, an annulus located on said bearing surface 10 and carrying said segmental valves, teeth on the periphery of said annulus, a valve-controlling shaft passing into said casing, bearings in said casing to support said shaft, and a worm on said shaft engaging the teeth of said 15 20 said annulus, substantially as set forth.

8. In a reversible turbine; the combination with a cylindrical casing, a revoluble shaft passing axially therethrough, end covers to the casing, bearings in said end covers to 25 carry said shaft, rotor disks keyed at a distance apart on said revoluble shaft, rotor blades pivoted at their rear radial edges to said rotor disks, and radially extending stop-pieces on said rotor disks extending between 30 35 40 said pivoted blades to limit their rocking motion, the casing having a steam inlet at one end and a steam outlet at the other end; of stationary guide rings within the casing one located adjacent to and in front of each rotor disk, each guide ring having a segmental series of guide vanes arranged in groups of forwardly directed and groups of backwardly directed vanes, said vanes being located opposite to said rotor blades, a number of slideable segment valves located in contact with the face of each guide ring, the proportions and number of said valves relatively to the groups of said vanes being such as to permit the segment valves to cover either the forward or the reversing vanes, or both, or to partially uncover either, means for carrying the valves of each stationary guide ring, and means for giving such valves requisite angular motions, substantially as set forth.

the periphery of said annulus, a valve-controlling shaft passing into said casing, bearings in said casing to support said shaft, a worm on said shaft engaging the teeth of said 50 annulus, and means for simultaneously operating all the said valve-controlling shafts to adjust the valves of one stationary guide ring simultaneously and proportionally to the segment valves of all the other stationary 55 guide rings, substantially as set forth.

9. In a reversible turbine; the combination with a cylindrical casing, a revoluble shaft passing axially therethrough, end covers to the casing, bearings in said end covers to 60 carry said shaft, rotor disks keyed at a distance apart on said revoluble shaft, rotor blades pivoted at their rear radial edges to said rotor disks, and radially extending stop-pieces on said rotor disks extending between 65 said pivoted blades to limit their rocking motion, the casing having a steam inlet at one end and a steam outlet at the other end; of stationary guide rings within the casing one located adjacent to and in front of each rotor 70 disk, each guide ring having a segmental series of guide vanes arranged in groups of forwardly directed and groups of backwardly directed vanes, said vanes being located opposite to said rotor blades, a number of slideable segment valves located in contact with the face of each guide ring, the proportions and number of said valves relatively to the groups of said vanes being such as to permit the segment valves to cover either the forward or the reversing vanes, or both, or to partially uncover either, means for carrying the valves of each stationary guide ring, and means for giving such valves requisite angular motions, substantially as set forth.

In witness whereof I have hereunto set my hand in the presence of two witnesses.

RICHARD CRAMP.
